UNITED STATES PATENT OFFICE

GUSTAV WIEDEKE, OF DAYTON, OHIO, ASSIGNOR TO GUSTAV WIEDEKE COMPANY, OF DAYTON, OHIO, A COPARTNERSHIP CONSISTING OF GUSTAV WIEDEKE, OTTO WIEDEKE, AND ROBERT WIEDEKE

OPERATING DEVICE FOR TUBE EXPANDERS AND THE LIKE

Application filed October 28, 1929. Serial No. 402,852.

This invention relates to an operating device for tube expanders and the like and is designed more particularly for use in expanding a tube in a header or like structure, but may be used in connection with tube cutters or like devices. Headers of the type here referred to are tubular structures having in one side wall thereof a series of openings to receive tubes and having in another wall thereof, usually at right angles to the first mentioned wall, a series of hand holes, there being one such hand hole adjacent to each tube receiving opening but not necessarily in line therewith. In expanding or cutting a tube which has been inserted in one of the tube receiving openings the expanding or cutting tool is introduced into the header through a hand hole adjacent to the tube which is to be expanded or cut and then inserted in the tube. Usually the tool is operated by a wrench having a straight handle which extends out through the hand hole adjacent to the tube in which the tool is mounted. The hand holes are of small size and the handle or lever can have only a short movement in the same, thus limiting to an objectionable extent the amount of movement that can be imparted to the tool upon each operation of the handle and rendering the operation slow and unsatisfactory.

One object of the invention is to provide an operating device for a tube expanding or cutting tool of such a character that it will impart a relatively large movement to the tool.

A further object of the invention is to provide such an operating device which will be very simple in its construction, inexpensive to produce and easily operated.

Other objects of the invention will appear as the device is described in detail.

In the accompanying drawings Fig. 1 is a side elevation, partly in section, of a header showing the invention installed therein; Fig. 2 is a vertical sectional view taken through the header at right angles to the view of Fig. 1; and Fig. 3 is a sectional detail view of the wrench.

In these drawings I have illustrated one embodiment of the invention and have shown

the same in connection with a header of a well known type but it will be understood that the device may take various forms and may be used in connection with headers or like devices of different kinds, the term "header" being herein used to designate any structure similar in character and function to that herein illustrated.

The header shown in the present drawings comprises a long tubular structure 5 having in one wall thereof a series of openings 6 to receive the ends of tubes 7. There may be any suitable number of these tube receiving openings and they may be spaced apart various distances. In that side of the header which extends at substantially right angles to the side in which the tube receiving openings are formed, is a second series of openings 8, which constitute hand holes, and there is one of these hand holes for each tube receiving opening, the corresponding hand holes and tube receiving openings being, in the present instance, arranged in the same transverse plane so that the hand hole is closely adjacent to the tube receiving opening. The hand holes are normally closed by suitable closures which are removed when access is to be had to the interior of the header, and which are not here shown.

When a tube in one of the tube receiving openings is to be expanded or cut the tube expanding or cutting tool is introduced into the header through the hand hole adjacent to the tube upon which it is to operate and is then inserted in the tube. In the present drawings the invention is illustrated in connection with a tube expanding tool, or expander. The particular tube expander here shown comprises the usual frame 9, expanding rollers, one of which is shown at 10, and a mandrel 11, which serves both to rotate the frame and to force the expanding rollers outwardly. The outer end of the mandrel is adapted to receive a suitable operating device. Preferably the operating device comprises a pawl and ratchet wrench and the wrench here shown consists of a ratchet wheel 12 having a square opening 13 to receive the square end 14 of the mandrel. A pawl carrier 15 is mounted for movement about the

axis of the ratchet wheel and has a substantially radial socket 16 to receive a handle or operating member. The pawl carrier supports one or more pawls adapted to engage the ratchet wheel and impart movement to the mandrel when the pawl carrier is moved in one direction and to ride over the ratchet teeth when the pawl carrier is moved in the other direction. In the present instance, I have shown two pawls 17 which are so arranged that when one pawl is in operative engagement with a tooth of the ratchet wheel the other pawl will be spaced substantially midway between two teeth, thus enabling the pawl carrier to pick up the ratchet wheel with a minimum of lost motion.

As has been explained, when the operating handle for the wrench extends outwardly through the adjacent hand hole 8 its movement is limited by the relatively small size of the hand hole and in order to secure a longer movement of the handle and a correspondingly greater movement of the tube expander I have provided a specially shaped handle of such a character that it will have substantially longitudinal movement through one of the hand holes and will impart a relatively large movement to the pawl carrier. The handle is indicated as a whole by the reference numeral 18 and it comprises an inner end portion 19 adapted to enter the socket 16 of the wrench and to extend lengthwise of the header. Extending laterally from the outer end of the part 19 of the handle is a second part 20 which, in the present instance, extends at substantially right angles to the part 19 and projects through a hand hole 8 spaced from the tube in which the tube expander is mounted. Preferably the part 20 of the handle extends through that hand hole next beyond the hand hole adjacent to the tube which is being expanded. At its outer end the part 20 of the handle is provided with a hand grip by means of which it may be operated and, in the present instance, a third part 21 of the handle extends from the outer end of the part 20 lengthwise of the header and in a direction away from the wrench. It will be apparent that when the part 21 of the handle is moved toward and from the header the transverse portion 20 thereof will move longitudinally through the hand hole 8, thereby permitting the inner end portion 19 of the handle to move the full width of the header, that is, from the position shown in full lines in Fig. 2 to the position shown in dotted lines, and consequently the handle will impart a very substantial movement to the wrench and to the tube expander. The handle is removably connected with the wrench and in practice the inner end thereof will be passed through the hand hole in which it is to operate and inserted in the socket of the wrench after the latter has been placed in position on the tube expander. The device is

very simple in its construction and can be produced at a very low cost and, further, it is very easy to operate. By its use I am able to impart to the tube expander a much greater movement than can be imparted thereto, in 70 a header, by other operating devices.

While I have shown and described one embodiment of my invention I wish it to be understood that I do not desire to be limited to the details thereof as various modifications 75 may occur to a person skilled in the art.

Having now fully described my invention, what I claim as new and desire to secure by Letters Patent, is:

1. A device for operating a tube expanding 80 or cutting tool, or the like, in a header having in one side thereof a longitudinal series of tube receiving openings and having a second longitudinal series of openings in a side thereof which is at a substantially right angle 85 to the first mentioned side, the openings of said second series being arranged adjacent to the respective tube receiving openings, said device comprising a pawl and ratchet wrench to be connected with a tool which has been 90 inserted in a tube in one of said tube receiving openings, and a handle for said wrench having a part extending from said wrench lengthwise of said header, and a part extending transversely to the axis of said 95 wrench and arranged to extend through an opening in said second series which is spaced longitudinally of said header from the tube in which said tool is mounted, and also having a part extending from the outer end of 100 said transverse part lengthwise of said header.

2. An operating device for a tube expanding tool or the like comprising a rotatable wrench to be supported by said tool, a handle for said wrench having a part extending substantially radially from said wrench, a part extending laterally from the first mentioned part and transversely to the axis of said wrench, and a part extending from the outer end of said lateral part in a direction approximately parallel with the first mentioned part.

In testimony whereof, I affix my signature hereto.

GUSTAV WIEDEKE.
